(No Model.)

E. H. ALLEN.
TROLLEY WIRE CROSSING.

No. 519,519.

Patented May 8, 1894.

UNITED STATES PATENT OFFICE.

EDWARD H. ALLEN, OF CRAMER'S HILL, NEW JERSEY.

TROLLEY-WIRE CROSSING.

SPECIFICATION forming part of Letters Patent No. 519,519, dated May 8, 1894.

Application filed February 2, 1894. Serial No. 498,893. (No model.)

To all whom it may concern:

Be it known that I, EDWARD H. ALLEN, a citizen of the United States, and a resident of Cramer's Hill, Camden county, New Jersey, have invented certain Improvements in Crossings for Trolley-Wires of Electric Railways, of which the following is a specification.

One object of my invention is to provide a simple and efficient form of bridge for guiding the trolley at points where two lines of electric railway cross each other, a further object being to prevent burning of the insulating block, forming part of said bridge structure. These objects I attain in the manner hereinafter set forth, reference being had to the accompanying drawings, in which—

Figure 1, is a perspective view of a crossing for electric railways constructed in accordance with my invention, the view being taken from the top. Fig. 2, is a similar view looking from the under side of the device. Fig. 3, is a longitudinal section, partly in elevation, of part of the device. Fig. 4, is a perspective view of the central insulating block. Fig. 5, is an enlarged transverse section on the line 5—5, Fig. 3; and Fig. 6, is an enlarged transverse section on the line 6—6, Fig. 3.

A and B represent the wires or electrical conductors of two electric trolley railway lines which cross each other at right angles, and D is a central block or plate of vulcanized fiber or other available insulating material which carries two pairs of projecting arms A' and B', the arms A' projecting in line with the conductor A and the arms B' projecting in line with the conductor B, each of said arms being suitably connected at its inner end to a block or plate a which is secured to the central block D.

Upon the arms A' and B' are formed jaws b which embrace or partially embrace the wires A or B as shown in Fig. 6, and upon the plate a are other jaws d which likewise embrace the wires A or B so that the entire crossing structure is hung upon and supported by the conductor wires. The jaws d of one pair of plates a (preferably those of the arms A') are higher than the other pair of jaws so as to carry one of the conductors above the other at the crossing point. On the under side of the central block D is a plate f which has a

central pin g and four arms i which form continuations of the arms A' B', but are separated therefrom by means of blocks m of insulating material suitably secured to the main block D. The arms i are thus insulated from the arms of which they form continuations so that the sparking point is transferred to a point outside the insulation instead of at the gap between the arms.

The central pin G serves to prevent any lateral deflection of the trolley when it is free from the influence of either of the guide arms i.

A crossing device of this character can be readily and cheaply manufactured, does not interfere with the continuity of the contact wires, and can be readily applied to the latter, after they have been strung and stretched, by simply bending the jaws b and d around the wires after the crossing device has been adjusted into its proper position thereon.

Having thus described my invention, I claim and desire to secure by Letters Patent—

1. The combination in a crossing device for electric railways, of a central block or plate of insulating material having a series of projecting arms forming continuations of the conductors and provided with clamping devices for engaging said conductors, substantially as specified.

2. The combination of the central insulating block or plate, the projecting arms and plates whereby said arms are secured to said insulating block, substantially as specified.

3. The combination of the central insulating block, the projecting arms, and the plates whereby said arms are connected to said insulating block, both the plates and arms having jaws for embracing the conductor wires and suspending the crossing structure therefrom, substantially as specified.

4. The combination of the central insulating block, with the trolley guide arms carried thereby, and insulating blocks whereby the continuity of said guide arms is interrupted so that the inner ends of the arms adjacent to the crossing point receive no current, substantially as specified.

5. The combination of the central insulating block, the trolley guide arms forming con-

tinuations of the conductor but separated from each other at the crossing point, and a central pin or stud serving to retain the trolley in proper lateral position at the crossing point, substantially as specified.

6. The combination of the central insulating block, the projecting arms forming continuations of the conductor, a plate secured to the under side of said insulating block, and 10 having arms which form continuations of the said projecting arms, and insulating blocks

interposed between the projecting arms and the arms on the plate, substantially as specified.

In testimony whereof I have signed my 15 name to this specification in the presence of two subscribing witnesses.

EDWARD H. ALLEN.
